UNITED STATES PATENT OFFICE.

DAVID R. COLLIER, OF GARDNER, MASSACHUSETTS, ASSIGNOR TO COLLIER-KEYWORTH COMPANY, OF GARDNER, MASSACHUSETTS, A CORPORATION OF MASSACHUSETTS.

HOOD ATTACHMENT FOR CHILDREN'S CARRIAGES.

No. 914,114.

Specification of Letters Patent.

Patented March 2, 1909.

Application filed June 20, 1908. Serial No. 439,612.

To all whom it may concern:

Be it known that I, DAVID R. COLLIER, of Gardner, in the county of Worcester and State of Massachusetts, have invented certain new and useful Improvements in Hood Attachments for Children's Carriages, of which the following is a specification.

This invention relates to children's carriages, and particularly to carriages adapted to be folded into compact form for storage and shipment.

The invention has for its object to provide a hood adapted to be detachably applied to a carriage, and to occupy any desired position which may be required to shelter the occupant of the carriage, and to be folded to an inoperative position either at the back of the seat or between the front of the seat and the dasher of the carriage, the hood being folded in the last named position preparatory to the operation of folding the carriage.

The invention consists in the several improvements which I will now proceed to describe and claim.

Of the accompanying drawings forming a part of this specification, Figure 1 represents a side elevation of a carriage provided with a hood attachment embodying my invention, the hood being shown in its operative position above the seat. Fig. 2 represents a side view of a portion of the carriage showing the hood folded behind the seat. Fig. 3 represents a view similar to Fig. 2 showing the hood folded between the front of the seat and the dasher. Fig. 4 represents a rear elevation of the carriage, the hood being adjusted as shown in Fig. 1. Fig. 5 represents a fragmentary view showing a portion of the hood and portions of the arms which support the same. Fig. 6 represents an enlargement of a portion of Fig. 4. Figs. 7, 8 and 9 represent side views of parts hereinafter referred to. Fig. 10 represents a section on line 10-10 of Fig. 4. Fig. 11 represents a section on line 11-11 of Fig. 4. Fig. 12 represents a section on line 12-12 of Fig. 10.

The same reference characters indicate the same parts in all the drawings.

The carriage body to which my improved hood attachment hereinafter described is applied, is here shown as of the same construction as represented in Letters Patent of the United States No. 862,711, dated August 6, 1907, but it will be understood that the subject matter of the present invention may be

applied to carriages otherwise constructed, and to carriages which are either of folding or non-folding construction.

In carrying out my invention, I provide a hood adapted to shield or protect the occupant of the seat 12 of the carriage, the hood, as here shown, being composed of a central bow 13, two side bows 14 pivotally connected at their ends to the ends of the central bow 13, and a flexible cover 15 attached to said bows, the hood being adapted to be folded by swinging the side bows inwardly toward the central bow, as indicated in Figs. 2 and 3, and extended to its operative position by swinging the side bows outwardly, as indicated in Fig. 1. The hood may be maintained in its extended position by means of a hinged brace composed of members 16, 16 pivotally connected with each other at 17, and pivoted at 18 to the bows 14. Preferably, the central bow 13 is provided at its ends with ears 19 (Fig. 5) projecting from opposite edges of the bow, the side bows 14 being connected with said ears by pivot bolts 20. The hood is provided at each end with a pair of supporting arms 21 and 22, these being pivotally connected at their upper ends by the bolts 20 with the end portions of the hood. The lower end portions of the supporting arms are adapted for engagement with an elongated pivot rod 23, which is supported by pivot-supporting members 24 mounted on a suitable part of the frame of the carriage, preferably the rear portion of the frame which supports the seat 12. The members 24 are preferably the ears which project upwardly from the frame of the carriage behind the seat, and support the handle 25 by which the carriage is pushed.

The pivot rod 23 is elongated so that it extends across the back of the carriage frame between the ears 24, as shown in Fig. 4, and is provided at one end with a head 26, its opposite end being screw-threaded and provided with a clamping wing nut 27.

Each arm 22 is provided at its lower end portion with a circular socket 28 (Fig. 8) formed to receive the pivot bolt 23, the arms 22 being, therefore, adapted to swing on the pivot bolt without having endwise movement relatively thereto, such movement being prevented by the close fit of the socket 28 on the bolt 23. Each arm 21 is provided in its lower end portion with an elongated slot 29 (Fig. 7) through which the pivot bolt passes, the arms

21 being, therefore, adapted both to swing upon the pivot bolt, and to slide lengthwise thereon. Each supporting member or ear 24 is provided with a circular socket 30 (Fig. 9) through which the bolt 23 passes, said socket being preferably a bushing inserted in an orifice formed for its reception in the ear 24, and provided with flanges 31, 31 (Figs. 10 and 11) which serve to connect the perforated ends 32 of the handle 25 with the ears 24, as shown in Figs. 10 and 11. Each supporting member or ear 24 is provided with a clutch part 33, preferably composed of a circular series of radial corrugations (Fig. 9) formed on the ear. Each arm 22 is provided with a complementary clutch part 34, preferably composed of a circular series of radial corrugations formed on a sheet metal disk 35, which is secured by rivets 36 to the arm 22, as shown in Fig. 8. The arms 22 are located adjacent to the ears 24 so that the clutch parts 33 and 34 are adapted to be engaged by pressure applied by turning the nut 27 inwardly on the bolt 23, this operation shortening the distance between the bolt head 26 and the nut 27, and causing the ears 24 to spring inwardly sufficiently to engage their clutch parts 33 with the clutch parts 34 on the arms 22.

A tubular strut 37 is mounted upon the pivot bolt 23 between the two pairs of hood-supporting arms, the ends of said strut bearing on the inner sides of the arms 21, and supporting the said arms against the pressure exerted upon them when the nut 27 is turned inwardly, the clutch parts 34 being thus rigidly backed so that they do not yield to the pressure exerted on the ears 24 by the bolt head and nut. It should be here noted that the ears 24, while practically rigid, are sufficiently springy to enable the clutch parts 33 to be engaged with and disengaged from the complementary clutch parts 34, the object of the described arrangement being to lock the hood-supporting arms rigidly to the supporting members or ears 24 in any desired position.

It will be seen that the arms 21 and 22 are pivoted to the hood at different points by the pivot bolts 20, said points being separated from each other by a sufficient distance to form a firm supporting base for the hood when the arms are locked to the supporting members 24. It will also be seen that the independent longitudinal movability of the arms 21 on the pivot bolt 23 enables the hood to be held when unfolded at any desired position over the seat, that is to say, the hood may be held directly over the seat, as shown in Fig. 1, or it may be tipped either forward or backward from said position while unfolded. The independent longitudinal movability of the arms 21 also enables the hood to be folded and stowed over the space behind the seat, as shown in Fig. 2, the pivot bolts 20 being then arranged one above

the other. The location of the supporting members or ears 24 behind the seat enables the hood to be stowed in a folded condition in front of the seat and behind the dasher, as shown in Fig. 3, preparatory to folding the carriage in the manner set forth in the above mentioned Letters Patent. I do not limit myself, however, to this arrangement of the supporting members or ears 24, as the same may be located at any suitable part of the frame, particularly when the folding of the hood with the carriage is not to be provided for.

The hood attachment, including the hood proper and the pairs of arms 21 and 22, may be removed bodily from the carriage by removing the nut 27 from the pivot bolt 23, and withdrawing the latter from the supporting members 24 and from the arms, the tubular strut 37 being detachable from the bolt so that it falls when the bolt is withdrawn. The connection between the handle 25 and the ears 24 is not affected by the removal of the hood attachment, the handle being permanently connected with the ears 24 by the tubular flanged bushings 30. It will be seen, therefore, that the carriage presents practically the same appearance, when the hood attachment is removed, as that shown in the above-mentioned patent. It will also be seen that, without detaching the hood from the carriage, the carriage may be folded as readily as if the hood were not present, the hood being first folded in front of the seat and behind the dasher, as shown in Fig. 3, after which the other parts of the carriage may be folded in the manner set forth in the above mentioned Letters Patent.

The elongated pivot rod 23 and the tubular strut 37 constitute parts of the hood attachment, these being removable from the carriage with the hood and its arms. To prevent the rotation of the pivot bolt with the clamping nut 27, I so form one of the sockets 30 and the corresponding part of the bolt, that the bolt cannot turn in the sockets. For example, the socket adjacent to the bolt head 26 may be provided internally with indentations 40, the corresponding part of the bolt being formed externally to engage the said indentations, as shown in Fig. 12.

An important feature of my invention is the provision of means for permitting the hood supporting arms 22 to oscillate, and for preventing longitudinal movement of said arms, the arms 21 being permitted both to oscillate and to move longitudinally. This construction enables both arms to be secured by the single pivot bolt 23 and the fixed ears 24 in a variety of positions, as illustrated in Figs. 1, 2, and 3.

I claim:

1. A carriage hood having at each end a pair of supporting arms pivoted at their upper ends to the hood at different points, 130

one of said arms having means at its lower end portion whereby the arm is adapted to swing on a supporting pivot, and is prevented from moving endwise, while the other 5 arm has means at its lower end portion for a swinging engagement with said pivot and a longitudinal sliding movement thereon.

2. A carriage hood having at each end a pair of supporting arms pivoted at their 10 upper ends to the hood at different points, one of said arms having at its lower end portion a circular socket adapted to swing on a supporting pivot, and to prevent endwise movement of the arm on the pivot, 15 while the other arm has at its lower end portion a longitudinal slot adapted to receive said pivot and permit longitudinal movement of the arm thereon.

3. A carriage hood having at each end a 20 pair of supporting arms pivoted at their upper ends to the hood at different points, one of said arms having at its lower end portion a circular socket whereby the arm is adapted to swing on a supporting pivot 25 and is prevented from moving endwise, and a clutch part adapted to engage a complementary clutch part on the carriage, the other arm having at its lower end portion a longitudinal slot, which permits both a 30 swinging and an endwise movement of said arm.

4. A foldable carriage hood comprising a central bow having ears at its ends, two side bows pivoted at their ends to said ears, 35 and a flexible cover attached to said bows, said hood having at each end a pair of supporting arms pivoted at their upper ends to said ears, one of said arms having means at its lower end portion whereby the arm is 40 adapted to swing on a supporting pivot, and is prevented from moving endwise thereon, while the other arm has means at its lower end, portion for a swinging engagement with said pivot, and a longitudinal sliding 45 movement thereon.

5. In combination, a carriage frame having a pair of pivot-supporting members provided with sockets, a pivot bolt inserted in said sockets, a hood having at each 50 end a pair of supporting arms the upper ends of which are pivoted at different points to the hood, one arm of each pair having a socket fitting said pivot bolt whereby the arm is pivoted to swing without endwise 55 movement, while the other arm is provided with a longitudinal slot whereby it is adapted both to swing and to move endwise on the pivot bolt, and means for rigidly securing the arms to the supporting members.

6. In combination, a carriage frame having a pair of pivot-supporting members provided with sockets, and with clutch parts adjacent to the sockets, a pivot bolt inserted in said sockets, a hood having at each 65 end a pair of supporting arms the upper ends

of which are pivoted at different points to the hood, one arm of each pair having a socket fitting said pivot bolt whereby the arm is pivoted to swing without endwise movement, while the other arm is provided 70 with a longitudinal slot whereby it is adapted both to swing and to move endwise on the pivot bolt, the socketed arm being provided with a complementary clutch part, and means carried by the pivot bolt for interlocking 75 the clutch parts on the socketed arms with clutch parts on the supporting members, whereby the arms may be rigidly secured to the supporting members, in different positions. 80

7. In combination, a carriage frame having a pair of socketed ears provided with clutch parts adjacent to the sockets, a pivot bolt inserted in the said sockets and provided with a head and with a clamping nut, 85 a hood having at each end a pair of supporting arms pivoted at their upper ends to the hood, one arm of each pair having an orifice adapted to receive said bolt, and a clutch part adapted to coöperate with one of the 90 fixed clutch parts, while the other arm has a slot adapted to receive the bolt, and permit the arm to slide thereon, and a tubular strut supported by the pivot bolt between said ears and supporting the arms against 95 inward pressure exerted by the head and nut of the pivot bolt, on the socketed ears.

8. A carriage frame having a seat, a dasher, and a pair of pivot-supporting members, combined with a foldable hood having 100 at each end a pair of supporting arms pivoted at their upper ends to the hood at different points, and at their lower ends to said members, one arm of each pair being slotted to permit a longitudinal movement on its 105 pivotal connection with the corresponding supporting member, the said supporting members being located behind the seat, whereby the arms may be adjusted to locate the folded hood between the seat and dasher. 110

9. A carriage frame having a pair of ears and a handle permanently connected with said ears by tubular bushings, combined with an elongated pivot bolt, detachably inserted in said bushings, a hood having arms pivoted 115 in pairs to its end portions, said arms being mounted to swing on the pivot bolt, and one arm of each pair being movable endwise independently, and means coöperating with said ears and pivot bolt for securing the arms to 120 the ears.

10. A carriage frame having a pair of ears, and a handle permanently connected with said ears by tubular bushings, said ears being provided with clutch parts, combined with 125 an elongated pivot bolt, having at one end a head bearing on one of said bushings, and at the other end an adjustable clamping nut bearing on the other bushing, a hood having arms pivoted in pairs to its end portions, the 130

said arms being mounted to swing on the pivot bolt, and one arm of each pair being movable endwise independently, while the other arm is provided with a complementary clutch part, and a tubular strut mounted on the rod between the ears, and supporting the arms and their clutch members against inward pressure exerted on the ears.

11. A carriage frame having a pair of ears provided with sockets, combined with an elongated pivot bolt detachably inserted in said sockets, a hood having arms pivoted to its end portions, and mounted to swing on

the pivot bolt, and means coöperating with said ears and pivot bolt for securing the arms 15 to the ears, one of the sockets and the corresponding part of the pivot bolt being formed to prevent the rotation of the bolt in the sockets.

In testimony whereof I have affixed my 20 signature, in presence of two witnesses.

DAVID R. COLLIER.
